DESIGN FOR A CIGARETTE DISPENSER

David W. Dunberg, New York, N. Y.

Application February 24, 1949, Serial No. 1,060

Term of patent 7 years

(Cl. D85—2)

To all whom it may concern:

Be it known that I, David W. Dunberg, a citizen of the United States of America, residing in New York, county of New York, and State of New York, have invented a new, original, and ornamental Design for a Cigarette Dispenser, of which the following is a specification, reference being had to the accompanying drawing, forming part thereof.

Fig. 1 is a front perspective view of a cigarette dispenser showing my new design.

Fig. 2 is a rear perspective view thereof in pulled out position.

I claim:

The ornamental design for a cigarette dispenser, substantially as shown.

DAVID W. DUNBERG.
